(57) **CLAIM**

The ornamental design for a recessed baffle trim, as shown and described.

DESCRIPTION

FIG. 1 is a bottom perspective view of one embodiment of a recessed baffle trim showing the new design;

FIG. 2 is a top perspective view of FIG. 1;

FIG. 3 is a side view of FIG. 1;

FIG. 4 is another side view of FIG. 1;

FIG. 5 is a bottom view of FIG. 1;

FIG. 6 is a top view of FIG. 1;

FIG. 7 is a bottom perspective view of a second embodiment of a recessed baffle trim showing the new design;

FIG. 8 is a top perspective view of FIG. 7;

FIG. 9 is a side view of FIG. 7;

FIG. 10 is another side view of FIG. 7;

FIG. 11 is a bottom view of FIG. 7;

FIG. 12 is a top view of FIG. 7;

FIG. 13 is a side view of FIG. 7 with the baffle trim portion in a rotated position; and,

FIG. 14 is a top perspective view of FIG. 7 with the baffle trim portion in a rotated position.

All structures shown in broken lines are for illustrative purposes only and form no part of the claimed design.
